LATCH MECHANISM

Edwin B. Jacobson, Grand Rapids, Mich., assignor
to Crampton Manufacturing Company, a cor-
poration of Michigan

Application February 17, 1949, Serial No. 76,898

9 Claims. (Cl. 292—336)

1

This invention is associated with latch mechanisms designed to provide a closing force when in locked position. This general type of device has come into wide use in connection with the doors of refrigerators in which it is not only desirable to secure the door, but to apply a considerable force to it in order to adequately develop the action of the sealing gasket. The present invention provides a series of performance features and other characteristics which are highly desirable, among which are a positive locking action, a releasing action achieved through a short handle pull, the application of a sealing force relatively independent of friction and the possible accumulation of manufacturing tolerances, outside mounting of the components of the device with respect to the door and body portion of the refrigerator, and a high degree of simplicity creating ease of assembly and minimizing the overall cost of manufacture.

The conventional construction of refrigerator doors involves a hollow sheet metal structure. The mounting system of the present invention provides a manner of attaching the lock mechanism to the sheet metal structure in such a way that forces are applied where the natural rigidity of the door is at a maximum. A fixed member of the lock mechanism, preferably in the form of a frame or housing, is so formed as to cooperate with the particular curvature of the door. Fastenings are provided for attaching this fixed member to the door at such a point that the curvature of the sheet metal is in the best position to resist the stresses generated by the locking forces. This feature, coupled with the ease of installation involved in applying the device to the exterior of the door rather than to the inside, has a strong tendency to decrease the net overall cost of providing the lock mechanism in the assembled refrigerator.

The moving parts of the present invention are so arranged in a fixed chassis as to provide a structure of minimum bulk. The arrangement of fixed and moving components of the present invention is such that a cantilever beam can be provided extending beyond the edge of the door and permitting the latch mechanism to engage a keeper that has no substantial projections outwardly toward the front of the refrigerator. In the preferred form of the invention, the arrangement of the components of a toggle mechanism is such as to provide a natural resetting system causing the latch mechanism to operate properly even though it is inadvertently tripped to closed position while the door is opened. These features

2

are all made possible by the linear arrangement of the components of the mechanism within the cantilever beam-type chassis. The arrangement of the bolt pivot point and the shape of the bolt dispose the various surfaces involved in such a relationship that the closing of the door with the bolt in locking position presents a slanted surface for engagement with the keeper having a natural tendency to swing the bolt toward retractive position so as to permit engagement with the holding portion of the keeper.

The present invention will be described in detail by an analysis of the particular embodiments which are illustrated in the accompanying drawings. In these drawings,

Figure 1 illustrates a section taken on a horizontal plane through a mechanism which is in the closed position. The mechanism illustrated in Figure 1 is of a toggle-type.

Figure 2 is a section indicating the same device shown in Figure 1 with the components in the unlocked position.

Figure 3 is an end of the device shown in Figures 1 and 2 with the section plane indicated at 1—1 showing the relationship of this figure with Figures 1 and 2.

Figure 4 is an illustration of a mechanism involving a biasing system operating upon the bolt which does not "pass over center."

Figure 5 illustrates the system indicated in Figure 4, with the components in the unlocked position.

Figure 6 shows a perspective view of the trigger member utilized in the mechanism shown in Figures 4 and 5.

Referring to Figure 1, the body portion of a refrigerator is generally indicated at 10 and the door at 11. A conventionally formed handle 12 is pivoted at 13 within the fixed housing 14. A spring 15 operates to return the handle 12 to the normal position independently of the bolt-positioning system. The various components of the latch mechanism shown in Figure 1 are securely mounted within the housing 14, which is attached to the door 11 by the fastening members 16 at points outwardly disposed with respect to the plane of the opening in the refrigerator 10 covered by the door 11. A rubber-like gasket 17 is provided between the body portion of the box and the door surrounding this opening to effectively seal the same against the passage of air. It is the purpose of the mechanism described herein to contribute sufficient force to the closing action to sufficiently compress the gasket 17 so that it may perform its required function.

The housing 14 is provided with the overhanging portion 18 carrying the pin 19 which acts as a fulcrum for the bolt 20. The bolt 20 cooperates with the fulcrum 19 at a slot 21, and a substantially cylindrical recess 22 is provided in the interior of the bolt for the spring 23. The spring 23 is, in effect, confined between the inner end of the recess 22 and the surface of the pin 19.

The body portion 10 of the refrigerator is provided with the keeper 24 having an anchoring point provided by the enlarged end 25. The bolt 26 is provided with the locking surface 28 disposed to cooperate with the anchoring point 25 to generate the required locking action. The bolt 20 is also provided with the curved recess 27 which cooperates with a similarly formed projection to form a pivot connection with the crank 28. The pin 29 provides a fulcrum support to the crank 28. The position of the pivot connection 27 with respect to the line of centers of the pins 29 and 19 establish the direction of the biasing action contributed by the toggle mechanism which includes the crank 28, the bolt 20, and the action of the spring 23.

The handle 12 is provided with the actuating extension 30 which is disposed to cooperate with the outer portion 31 of the crank 28. As the handle 12 is actuated, rotation takes place about the pivot 13, causing the actuating extension 30 to cooperate with the outer portion 31 of the crank 28 and impart rotation thereto. Such rotation causes the pivot connection 27 between the bolt and crank to approach the line of centers between the pins 29 and 19, and causes the mechanism to snap to the open position.

As the door 12 is swung to the closed position, the contact portion 32 of the trigger 33 collides with the outer end of the keeper 24. This action causes the trigger member 33 to rotate about the fulcrum support 34, resulting in bringing the arm 35 to bear upon the top of the bolt 20. Figure 2 illustrates the position of the components just previous to the point of contact between the contact portion 32 and the keeper 24. As the trigger 33 continues to rotate about its fulcrum, the bolt 20 is urged into a position in which the pivot connection 27 passes across the line of centers between the pins 19 and 29 causing the bolt to snap to the locked position shown in Figure 1. As the door handle is actuated to open the door, the upsetting of the toggle system into the position shown in Figure 2 causes a force to be applied to the keeper 24 by the contact surface 32 resulting in an impulse being imparted to the door in the direction of the open position. It will be noted that the surface 36 of the inner side of the housing 14 is so disposed as to operate as a stop limiting the movement of the toggle system in the direction of the unlocked position. If the toggle is accidentally tripped while the door is open, the structure of the housing prevents over-rotation of the crank.

Referring to Figures 4 and 5, a latch mechanism is shown in which the action of the bolt-positioning system and of the trigger are different from those indicated in the mechanism shown in Figures 1 and 2. In Figures 4 and 5, the pivot contact 37 between the bolt 38 and crank 39 never quite reaches the line of centers between the crank fulcrum 40 and the bolt fulcrum 41. This mechanism does not have the characteristic of snapping to the open position which is to be found in the mechanism shown in Figures 1 and 2. As the handle 11 is pulled, the actuating extension 30 cooperates with the outer portion 42

5 of the crank 39 to induce rotation thereof about the pin 40. Such action continues until the latching surface 43 of the crank 39 reaches a position where the engaging surface 44 of the trigger 45 can cooperate under the action of the spring 46. The components are shown in this relationship in Figure 5. As the door is swung to the closed position, the contact surface 47 of the trigger 45 effects engagement with the outer portion of the keeper plate 24 and forces the trigger from the position shown in Figure 5 to that indicated in Figure 4. This movement of the trigger releases the restraint placed upon the biasing action of the spring 46, and permits the net biasing effect of the system to come to bear and contribute the required locking force. The assembled relationship of the trigger member 45 and the crank 39 provides for the two opposite arms 49 and 50 to straddle the portion 51 of the crank 39 which is cut away on each side as shown to provide for the latching surfaces 43.

The particular embodiments of the present invention which have been illustrated in the accompanying drawings and are discussed herein are for illustrative purposes only, and are not to be taken as limitations upon the scope of the appended claims. In these claims it is the intent of the inventor to claim the entire scope of the invention to which he is entitled in view of the prior art.

I claim:

1. A latch mechanism for cooperation with a keeper to secure a door in closed relationship with a container, comprising: a fixed member; means forming a toggle system comprising a bolt having a locking portion for cooperation with said keeper, and crank means pivotally engaging said bolt, said bolt and crank means being pivotally mounted on said fixed member at points remote from said locking portion, and said locking portion having a path of movement located between said pivotal mountings and directed substantially perpendicularly to a line connecting said mountings; biasing means urging said bolt and crank means together; stop means limiting the movement of said bolt in a direction away from said keeper; and actuating means for imparting rotation to a member of said toggle system about its fulcrum to engage and disengage said bolt from said keeper.

2. A latch mechanism for cooperation with a keeper to secure a door in closed relationship with a container, comprising: a fixed member having an overhanging portion disposed to pass over and beyond said keeper as said door is closed; means forming a toggle system comprising a bolt having a locking portion for cooperation with said keeper, and crank means pivotally engaging said bolt, said crank being pivotally mounted on said fixed member at a point remote from said locking portion, and said locking portion having a path of movement located between said pivotal mountings and directed substantially perpendicularly to a line connecting said mountings; fulcrum means associated with said overhanging portion for supporting said bolt at a point remote from said locking portion; biasing means urging said bolt and crank means together; stop means limiting the rotation of said bolt in a direction away from said keeper; and actuating means for imparting rotation to a member of said toggle system about its fulcrum to engage and disengage said bolt from said keeper.

3. A latch mechanism for cooperation with a

keeper to secure a door in closed relationship with a container, comprising: a fixed member having an overhanging portion disposed to pass over and beyond said keeper as said door is closed; means forming a toggle system comprising a bolt having a locking portion for cooperation with said keeper, and crank means pivotally engaging said bolt, said crank being pivotally mounted on said fixed member at a point remote from said locking portion, and said locking portion having a path of movement located between said pivotal mountings and directed substantially perpendicularly to a line connecting said mountings; fulcrum means associated with said overhanging portion for supporting said bolt at a point remote from said locking portion; biasing means urging said bolt away from said fulcrum; stop means limiting the rotation of said bolt in a direction away from said keeper; and actuating means for imparting rotation to a member of said toggle system about its fulcrum to engage and disengage said bolt from said keeper.

4. A latch mechanism for cooperation with a keeper to secure a door in closed relationship with a container, comprising: a fixed member having an overhanging portion disposed to pass over and beyond said keeper as said door is closed; means forming a toggle system comprising a hollow bolt having a locking portion for cooperation with said keeper, and crank means pivotally engaging said bolt adjacent said locking portion, said crank being pivotally mounted on said fixed member at a point remote from said locking portion; fulcrum means associated with said overhanging portion for slideably supporting said bolt at a point remote from said locking portion; biasing means disposed within said hollow bolt and urging it away from said fulcrum; stop means limiting the rotation of said bolt in a direction away from said keeper; and actuating means for imparting rotation to a member of said toggle system about its fulcrum to engage and disengage said bolt from said keeper.

5. A latch mechanism for cooperation with a keeper to secure a door in closed relationship with a container, comprising: a fixed member having an overhanging portion disposed to pass over and beyond said keeper as said door is closed; means forming a toggle system comprising a bolt having a locking portion for cooperation with said keeper, and crank means pivotally engaging said bolt adjacent said locking portion, said crank being pivotally mounted on said fixed member at a point remote from said locking portion; fulcrum means associated with said overhanging portion for supporting said bolt at a point remote from said locking portion; biasing means urging said bolt away from said fulcrum; stop means limiting the rotation of said bolt in a direction away from said keeper; trigger means pivotally mounted on said fixed member and having an operating member positioned to bear against said toggle system adjacent said locking portion, and having a contacting member adapted to cooperate with a surface fixed with respect to said keeper to rotate said trigger in a direction causing said locking portion to move toward locking position; and actuating means for imparting rotation to a member of said toggle system about its fulcrum to disengage said bolt from said keeper.

6. A latch mechanism for cooperation with a keeper to secure a door in closed relationship with a container, said keeper being attached to the outer side surface of said container, comprising: a fixed member adapted to be secured to the

outer surface of said door at points outwardly disposed with respect to the plane of the opening covered by said door, said member having an overhanging portion disposed to pass over and beyond said keeper as said door is closed; bolt means; supporting means associated with said overhanging portion for said bolt means; and means for interposing said bolt means between said support means and said keeper and withdrawing said bolt from interposed position.

7. A latch mechanism for cooperation with a keeper to secure a door in closed relationship with a container, said keeper being attached to the outer side surface of said container, comprising: a fixed member adapted to be secured to the outer surface of said door at points outwardly disposed with respect to the plane of the opening covered by said door, said member having an overhanging portion disposed to pass over and beyond said keeper as said door is closed; a bolt; fulcrum means associated with said overhanging portion for supporting said bolt; and means for rotating said bolt to and from interposed position between said fulcrum means and said keeper.

25 8. A latch mechanism for cooperation with a keeper to secure a door in closed relationship with a container, said keeper being attached to the outer side surface of said container, comprising: a fixed member adapted to be secured to the

30 outer surface of said door at points outwardly disposed with respect to the plane of the opening covered by said door, said member having an overhanging portion disposed to pass over and beyond said keeper as said door is closed; a bolt;

35 supporting means associated with said overhanging portion for said bolt; biasing means associated with said overhanging portion urging said bolt toward said keeper; and means for interposing said bolt between said support means and said keeper and withdrawing said bolt from interposed position.

9. A latch mechanism for cooperation with a keeper to secure a door in closed relationship with a container, said keeper being attached to the outer side surface of said container, comprising: a fixed member adapted to be secured to the outer

45 surface of said door at points outwardly disposed with respect to the plane of the opening covered by said door, said member having an overhanging portion disposed to pass over and beyond said keeper as said door is closed; a bolt; supporting means associated with said overhanging portion for said bolt; biasing means associated with said overhanging portion urging said bolt toward said

50 keeper, and means for interposing said bolt between said support means and said keeper and withdrawing said bolt from interposed position; and means for moving said bolt against said biasing means during said withdrawing action.
